Des. 203,739
Patented Feb. 15, 1966

203,739

HAIR NET CAP

Ruby R. Brill, 7123 Cornelia Lane, and Grace B. Parrott,
1407 El Patio Drive, both of Dallas, Tex.

Filed June 8, 1965, Ser. No. 85,622

Term of patent 14 years

(Cl. D3—13)

Fig. 1

Fig. 2

Fig. 3

Fig. 4

Fig. 6

Fig. 5

FIG. 1 is a front elevational view of a hair net cap showing my new designs;

FIG. 2 is a side elevational view thereof, the side opposite being a mirror image thereof;

FIG. 3 is a top perspective view;

FIG. 4 is a top plan view;

FIG. 5 is a bottom plan view; and

FIG. 6 is a fragmentary rear elevational view thereof showing the opening.

The ties at the bottom of the hair net cap in FIGS. 1, 2 and 6 have been shown broken away for convenience of illustration.

We claim:

The ornamental design for a hair net cap, as shown and described.
